UNITED STATES PATENT OFFICE.

EDWARD P. WATSON, OF FLORAL PARK, NEW YORK.

WHEELED-TOY DEVICE.

Application filed November 26, 1926. Serial No. 150,783.

This invention relates to toys and particularly to wheeled toys adapted to be drawn over a floor or other surface; and the object of the invention is to provide a device of this class with a rotatable body in operative connection with one set of wheels of the device, whereby in the progress of the toy over a floor or other surface, said body will be rotated; a further object being to provide other rotatable members supported in connection with said body and rotatable therein and in different directions in the rotation of said body; and with these and other objects in view, the invention consists in a device of the class and for the purpose specified, which is simple in construction and operation, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view of a toy device made according to my invention, with parts of the construction broken away and in section; and,

Fig. 2 is an end view of the toy, with part of the construction broken away and in section.

In practice, I provide a base or frame 5 which may be constructed in any desired manner, and which in the construction shown, is fashioned from sheet metal. The side walls of said frame, adjacent each end thereof, are extended downwardly to form bearings 6 for the axles 7 of front and rear wheels 8 and 9.

Centrally of the frame 5 is a conical standard 10 in which a vertical shaft 11 is mounted, the upper end of said shaft being enlarged as seen at 12. Supported in connection therewith, is a body 13, which in the construction shown, is composed of a strip of metal having top and bottom portions 14 and 15 coupled together by end walls 16. The end portions of the walls 14—15 extend downwardly in parallel relation at an angle to horizontal and vertical planes in order that the beveled faces 17 of friction disks or wheels 18 may operate in connection with the conical standard 10 as clearly seen in Fig. 2. Members 19 of any desired shape, form and construction are supported in connection with the body 13 or the end

portions thereof and preferably between the walls 14 and 15, and are further coupled with the disks 18 whereby said members will be rotated in the body 13 when said body is rotated by the movement of the toy over a floor or other surface.

In the construction shown, the members 19 are mounted on shafts 20 coupled with the disks 18. The upper ends of said shafts are provided with flag devices 21, and similar flag devices 22 are supported centrally of the top wall 14 of the body 13. In this connection, it will also be understood that any suitable device or element may be used instead of said flags to give the desired ornamentation, character and attractiveness to the device, to be impressive and appealing to a child.

Secured to the lower end of the shaft 11 beneath the frame 5 is a pulley 23 around which is passed a belt 24 which passes around a pulley 25 secured to the axle 7 of the front wheels 8 in the construction shown. A pull string or handle device 26 is coupled with the front end of the frame 15 to manipulate the same over a floor or other surface. In the rotation of the wheels of the toy in its movement, the body 13 will be rotated, and in this operation, the engagement of the friction disks 18 with the conical standard 10 will cause the members 19, together with the devices 21 to be rotated in different directions in the body 13, producing an attractive and pleasing effect, which will entertain both young and old.

As previously stated, my invention is not necessarily limited to the shape, form or construction of the members 19, and the devices 21 and 22; nor am I necessarily limited to the specific form and construction of the body 13, nor the method of its operation, and various other changes in and modifications of the construction herein shown and described, may be made within the scope of the appended claims without departing from the spirit of my invention or sacrificing its advantages.

Having fully described my invention, what I claim as new and desire to secure by Letters Patent, is:—

1. A toy device comprising a frame, wheels mounted in connection with said frame for movably supporting the same on a surface, a standard on said frame, a body rotatably mounted in connection with the upper end of said standard, means for actuating said

body in the movement of the toy over a surface, members rotatably mounted in said body, means on said members engaging said standard whereby in the rotation of said body, said members are rotated in said body, said last named means comprising friction disks engaging the periphery of said standard, and said standard being conical in form, and said disks having beveled faces engaging said standard.

2. A toy device comprising a frame, wheels mounted in connection with said frame for movably supporting the same on a surface, a standard on said frame, a body rotatably mounted in connection with the upper end of said standard, means for actuating said body in the movement of the toy over a surface, members rotatably mounted in said body, means on said members engaging said standard whereby in the rotation of said body, said members are rotated in said body, said last named means comprising friction disks engaging the periphery of said standard, said standard being conical in form and said disks having beveled faces engaging said standard, and other devices movable with said members.

3. A toy device of the class described, comprising a frame having downwardly directed wheel bearings in connection with which wheels and axles are supported, a standard on said frame, said standard having a tapered outer face, a body supported at the upper end of the standard and rotatable thereon, means whereby said body will be rotated in the movement of the toy over a floor surface, the ends of said body projecting beyond the standard being arranged angularly with reference to a horizontal plane, members rotatably mounted in connection with the angular ends of said body, and friction disks coupled with said members and cooperating with the standard for imparting rotary movement to said members in the rotation of said body.

4. A toy device of the class described, comprising a frame having downwardly directed wheel bearings in connection with which wheels and axles are supported, a standard on said frame, said standard having a tapered outer face, a body supported at the upper end of the standard and rotatable there-

on, means whereby said body will be rotated in the movement of the toy over a floor surface, the ends of said body projecting beyond the standard being arranged angularly with reference to a horizontal plane, members rotatably mounted in connection with the angular ends of said body, friction disks coupled with said members and cooperating with the standard for imparting rotary movement to said members in the rotation of said body, and said friction disks having beveled faces cooperating with the outer face of the standard.

5. A wheeled toy comprising a frame, wheels for supporting and moving said frame over a surface, a horizontally arranged body mounted in spaced relation to and arranged over said frame, a vertical axis on said body and extending through and supported in said frame and in operative connection with said wheels, whereby in the movement of the toy, said body is rotated, a member arranged at one side of the axis of said body and carried by and movable therewith, a vertical axis in said member in spaced relation to the axis of said body and angularly disposed with reference thereto and on which said member is mounted, and means whereby said member may be rotated in said body in the rotation of said body.

6. A wheeled toy comprising a frame, wheels for supporting and moving said frame over a surface, a horizontally arranged body mounted in spaced relation to and arranged over said frame, a vertical axis on said body and extending through and supported in said frame and in operative connection with said wheels, whereby in the movement of the toy said body is rotated, members arranged at the opposite sides of said body and carried by and movable therewith, said members having vertical shafts rotatable in said body and arranged angularly with reference to the axis of said body and means whereby said members may be rotated in different directions in said body in the rotation of said body.

In testimony that I claim the foregoing as my invention I have signed my name this 22nd day of November, 1926.

EDWARD P. WATSON.
